UNITED STATES PATENT OFFICE.

HENRY CHARLES BAILEY, OF KENT, OHIO, ASSIGNOR TO JAMES DWIGHT FOOT, OF NEW YORK, N. Y.

FILE-CUTTING MACHINE.

SPECIFICATION forming part of Letters Patent No. 625,235, dated May 16, 1899.

Application filed January 24, 1899. Serial No. 703,259. (No model.)

To all whom it may concern:

Be it known that I, HENRY CHARLES BAILEY, a citizen of the United States, residing at Kent, in the county of Portage and State of Ohio, have invented certain new and useful Improvements in File-Cutting Machines, of which the following is a specification.

My invention has for its object to cut two file or rasp blanks simultaneously and yet 10 produce articles which are regularly cut and uniform in character; and to this end my invention consists in providing a file or rasp cutting machine with blank-holding beds capable of a free rocking movement, adapting 15 them to accommodate the positions of the blanks to the action of the cutting tool or tools, as fully set forth hereinafter and as illustrated in the accompanying drawings, in which—

20 Figure 1 is a side elevation showing one form of file-cutting apparatus provided with my improvements. Fig. 2 is an end view. Fig. 3 is a side elevation of the carriage, bed, and their support. Fig. 4 is a plan of Fig. 3. 25 Fig. 5 is an end view of Fig. 3. Figs. 6 and 7 are diagrammatic views showing in an exaggerated way the capacity of the blank-supports to accommodate themselves to the tool under different positions. Fig. 8 is a diagram 30 illustrating certain modifications.

My improvements are adapted to be used with file-cutting and in some cases with rasp-cutting machines of different constructions; but as shown they are applied in machines 35 having a base A, horizontal groove B, carriage C, sliding longitudinally in said groove, and a propelling-screw D, with which the carriage may be connected, as desired, by turning down a wing F, while a cutter E reciprocates above 40 the carriage under the action of well-known devices not necessary to be described.

Upon the carriage is mounted a member, which I term a "support" G, so as to be capable of rocking upon its central axis. This 45 support may vibrate upon a longitudinally-extended pivot as trunnions at the ends or may be otherwise supported upon a pivot so as to yield when pressure is brought against the top face upon either side of the longitudinal center. A preferable arrangement consists in recessing longitudinally both the sup-

port and the carriage, so as to receive a bearing-bar a, fitting said recesses, there being sufficient room between the lower face of the support and the upper face of the carriage to permit the desired rocking of the former. In recesses in the carriage, on opposite sides of the longitudinal center, are inserted springs b, which bear upon the support and tend to maintain it in a level position.

There are two beds H H for the file-blanks, arranged parallel to each other and each mounted to vibrate on its longitudinal center upon a bearing at the upper side of the support G. While any suitable means may be employed for so mounting the beds, I prefer to recess the upper face of the support and under faces of the beds to receive bearing-bars c c.

Suitable means is provided for normally 70 maintaining the level positions of the beds— as, for instance, a transverse strip of rubber d, bolted to the upper face of each bed, tending to maintain both faces on the same plane, but permitting each bed to rock to a certain 75 extent independently of the other. The upper face of each bed may be provided with a zinc or other facing, as usual, and each bed is also provided with a strap e, for slipping over and holding the tang of a blank X, and side 80 bearings i, and to prevent the longitudinal movement of the beds the carriage C is provided at one end with a stop or bearing plate f and at the opposite end with a standard g, through which extends screw-bolts h h, that 85 may be turned to bring their ends so close to the ends of the beds as to prevent longitudinal movement of the latter.

The faces of the beds and of the file-blanks thereon are below the cutting-tool E, the reciprocation of which, in connection with the travel of the carriage, results in cutting the blanks transversely or diagonally at successive points.

Heretofore it has not been practicable to 95 accurately cut a number of files simultaneously in a single machine, as owing to wear of the cutter or imperfect adjustments of the parts one blank would be cut deeper than another or deeper upon one side than 100 upon the other, resulting in imperfect and irregular articles. By the above means, how-

ever, the cut upon each blank is regular and the articles produced are of uniform character, inasmuch as each bed and the face of the blank thereon will always accommodate itself 5 to the inclination or position of that portion of the cutting edge of the tool which acts upon the blank—that is, in the operation of cutting the face of the blank and the edge of the tool will be maintained parallel to each 10 other and the blank cannot be cut deeper at one edge than at the other. Further, the two blanks will be cut uniformly, even if one should be thicker than the other, because the support for the blanks will yield as soon as the 15 cutting edge of the tool is brought against the face of the blank which is most elevated and until both faces are in contact with the cutting edge, after which the cutting operation upon both will be uniform.

20 While I have referred to the use of a single tool or cutter operating upon both blanks, there may be two cutters mounted upon a reciprocating carrier or head, as shown in diagram Fig. 8. In such case it is immaterial 25 whether or not the cutters wear uniformly. In Fig. 8 I show also bearing-heads a' c' , formed upon the support C.

30 In Fig. 6 I illustrate diagrammatically the positions taken by the parts with a cutter having a somewhat inclined cutting edge and blanks of different thicknesses.

35 In Fig. 7 I indicate the action, assuming the cutting edge of the tool to present different angles to the different blanks.

40 I may remark that while I have shown the bed in a V shape this particular shape is not necessary, as the bed may be a square or flat bed or other shape—as, for instance, a half-round bed—without affecting the general principles of the invention.

Without limiting myself to the constructions shown, I claim as my invention—

1. The combination with the traveling carriage of a file-cutting machine, of a blank-supporting bed mounted upon the carriage 45 to move therewith and being free to rock, and a longitudinally-extending pivot upon which the bed is supported, substantially as set forth.

50 2. The combination with the traveling carriage of a file-cutting machine, of a blank-supporting bed mounted upon the carriage to move therewith and being free to rock, and a longitudinally-extending pivot upon which 55 the bed is supported with its axis below the bed, substantially as set forth.

3. The combination with the traveling car-

riage, of a file-cutting machine, of a support free to rock on said carriage, a pivot interposed between the carriage and support upon 60 which the latter may rock, and two blank-supporting beds each pivotally mounted upon said support and free to rock, substantially as set forth.

4. The combination of a carriage, a support 65 having a longitudinal central pivotal bearing on said carriage, and two parallel blank-supporting beds each having a longitudinal central pivotal bearing on said support and being free to rock thereon, substantially as set 70 forth.

5. In a file-cutting machine, two file-blank beds free to rock, combined with a support upon which the file-blank beds are carried, a longitudinally-extending pivot upon which 75 the support is mounted, and springs normally tending to hold the support in a horizontal position, substantially as set forth.

6. In a file-cutting machine, a support, a longitudinally-extending pivot upon which 80 the support is mounted and upon which it may rock, and springs normally tending to hold the support in a horizontal position, combined with two parallel blank-beds, two longitudinally-extending pivots, carried by the 85 support, upon which the blank-beds are respectively supported and upon which they may rock independently, and springs normally tending to hold the blank-beds in a horizontal position, substantially as set forth. 90

7. The combination of the carriage of a file-cutting machine, a central bearing-bar, and recessed support resting thereon, two parallel bearing-bars fitting recesses in the face of said support, and recessed blank-beds 95 resting on said bearing-bars, substantially as set forth.

8. The combination of the carriage of a file-cutting machine, a central bearing-bar, and recessed support resting thereon, two 100 parallel bearing-bars fitting recesses in the face of said support and recessed blank-beds resting on said bearing-bars and springs arranged to normally maintain the support and bed in level positions, substantially as set 105 forth.

In testimony whereof I have signed my name to this specification in the presence of two subscribing witnesses.

HENRY CHARLES BAILEY.
